UNITED STATES PATENT OFFICE.

JACOB M. WINTROB, OF PHILADELPHIA, PENNSYLVANIA.

ELECTRIC IRON.

Application filed August 7, 1922. Serial No. 580,094.

My invention relates to new and useful improvements in an electric iron of the type in which a removable, interchangeable heating element is used so that when one is 5 burned out, damaged or otherwise impaired it may be removed and replaced by a new one.

The principal object of the invention is to provide a simple and compact device of 10 this character which may be readily and quickly taken apart by a person unskilled in mechanical structures, such as a housewife for instance, the heating element changed and the parts reassembled and fastened together.

Another object of the invention is to provide a separable iron or an iron having separable units detachably fastened together.

A further object of my invention is to provide an exceedingly simple and effective arrangement for fastening the parts together which will simultaneously force one element, unit or part forwardly of and toward the other element insuring a tight joint.

A still further object of this invention is to utilize parts of the iron as a support or stand when the iron is temporarily set aside during the time articles, which are being pressed, are rearranged or changed.

Yet another object of the invention is to produce an electric iron comprising a base having a recess to receive and hold a removable heating element, said base having an undercut hole at one end and a screw arranged at an angle at the other end, a top provided with a lug or tongue arranged at an angle for registration with the undercut hole and having a beveled surface in which is a slot to register with the screw, a handle carried by the top and a wing nut for mounting upon the screw to engage the bevel surface whereby the top may be tightly but removably secured to the base, said wing nut in conjunction with the handle acting as a stand or support when the iron is tilted.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing

forming a part of this application, in which:

Fig. 1 is a sectional side elevation of an electric iron embodying my invention.

Fig. 2 is a side elevation thereof in a 60 tilted position.

Fig. 3 is a plan view of the base with the top removed.

Fig. 4 is an end view of the top.

Fig. 5 is an enlarged side elevation of the 65 wing nut.

In carrying out my invention as here embodied, 2 represents the base of an iron having a smoothing surface 3 and provided with a recess 4 to receive and hold a removable 70 interchangeable heating element 5 of any suitable well known construction. At one end of the base, preferably the forward end, is formed an undercut hole 6 or in other words the hole is formed at an angle to the 75 smoothing surface of the base the same projecting downwardly and forwardly. At the other or rear end of the base is located a screw or bolt 7 it being mounted in the base in any suitable manner preferably by casting the base about it and this screw bolt is arranged in an upwardly and outwardly projecting position substantially at the same angle as the undercut hole 6. This bolt receives the butterfly or wing nut 8 the 80 extremities of the wings 9 in a certain case acting as feet as will be later described.

The top 10 to which is attached the handle 11 carries the electrical conductors including contact posts 12 and this top is adapted 90 to set upon the upper edge of the base preferably with a sheet of asbestos 13 interposed between them, said asbestos sheet being secured to the inner surface of the top. Projecting from the bottom of this top element 95 adjacent one or its forward end is an angular lug or tongue 14 projecting downwardly and outwardly for registration with the undercut hole 6 while at the other or rear end of said top is formed a bevel surface 15 100 lying at an acute angle to the bottom or inner face of the top and the smoothing surface of the base and in this surface or said other end is formed an opening 16 preferably in the form of a slot, as plainly shown 105 in Fig. 4, so as to readily register with the screw or bolt 7 and when the top is in place upon the base, as shown in Fig. 1, the butterfly or wing nut 8 will engage the bevel surface 15 to securely draw the parts to 110

gether and make a tight joint between the base and top units.

When the parts are drawn together the butterfly or wing nut must set transversely 5 of the iron body in order that the wings 9 thereof will act as feet in conjunction with the adjacent end of the handle 11 when the iron is tilted, as shown in Fig. 2, thus acting as a temporary stand or support for the 10 iron during the time the work is being changed or rearranged thereby preventing the iron from scorching the object on which it is set and eliminating the necessity of using a separate or independent stand which 15 being of metal oftentimes has a tendency to mar or otherwise damage the smoothing surface of the iron.

From the foregoing description it will be noted that when it becomes necessary to remove or change the heating element the butterfly or wing nut is backed off of the screw permitting the rear or that end of the top engaged by said nut to be lifted and the tongue 14 withdrawn from the undercut hole 6 so that said top may be separated and entirely removed from the base giving access to the heating element so that it may be removed and reduced or another substituted therefor.

After the necessary change has been made 30 the tongue 14 is inserted in the undercut hole 6 and the opening 16 caused to register with the screw or bolt 7 then by drawing up on the butterfly or wing nut 8 it will be moved into engagement with the bevel end 35 or surface 15 of the top and because of said bevel end and the annular portion of the screw or bolt 7 said top will be forced endwise or forwardly of the base and in conjunction with the tongue 14 will cause the top to be forced downwardly or toward the base thereby forming a tight joint between the two members.

Of course I do not wish to be limited to 45 the exact details of construction as herein shown as these may be varied within the limits of the appended claims without departing from the spirit of my invention.

Having thus fully described my invention, what I claim as new and useful is:—

1. An iron comprising a base, a top coacting therewith, means for detachably connecting the top to the base, said means including a butterfly or wing nut, said nut when in place having its wings projecting 55 transversely of the iron and a handle fixed to the top, said handle cooperating with the wing nut when the iron is in a tilted position to act as a stand or support.

2. An iron comprising in combination, a 60 base having an undercut hole at its forward end, a bolt located at the rear of the base and projecting upwardly and rearwardly at an angle to the smoothing surface of said base, a separate top for coaction with the base and having a bevel surface at its rear end in which is formed an opening for registration with the bolt, a tongue carried by the forward end of the top for registration with the undercut hole, said tongue projecting downwardly and forwardly at an angle to the inner face of said top, a wing nut having threaded connection with the bolt and adapted to engage the bevel surface of the top for forcing the latter forwardly and in conjunction with the tongue coacting with the undercut hole forcing the top toward the base to produce a tight joint, said wing nut when tightened lying transversely of the iron and a handle carried by 70 the top for operating the iron and cooperating with the wing nut when the iron is tilted to act as a stand or support.

3. An iron comprising a base having an undercut hole at its forward end, a coacting 75 top member having an opening at its rear end and provided with a bevel surface in the region of said opening, a tongue on the forward end of the top member for insertion in the undercut hole, an inclined bolt 80 at the rear of the bottom for registration with the opening in the top member, and means having threaded engagement with the bolt and bearing on the beveled surface of said top to force the latter into close contact with the bottom.

In testimony whereof, I have hereunto affixed my signature.

JACOB M. WINTROE.
